(57) **CLAIM**

The ornamental design for a heat conducting unit, as shown and described.

DESCRIPTION

FIG. 1 is a perspective view of a heat conducting unit showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is an enlarged cross-sectional view taken from line 8-8 in FIG. 2.

The stippling in the drawings indicates a contrast in material.
